MACHINE FOR MAKING FOUNDRY CORES
AND MOLDS

Heinrich Schulte Herbruggen, Hagen-Kabel,
Germany, assignor to The Constructional En-
gineering Company Limited, Birmingham,
England, a company of Great Britain

Application January 24, 1949, Serial No. 72,460
In Great Britain March 11, 1948

4 Claims. (Cl. 22—10)

1

This invention relates to improvements in machines for making foundry cores and moulds and refers particularly to machines of the type in which prepared sand is fed from a hopper or the like into a chamber from which it is forced by air under pressure through openings in the bottom of the chamber into a core box or moulding box which is supported on a table movable vertically by hydraulic or pneumatic means to hold the core box or moulding box against the blowing chamber for filling. A machine of this type is described in the specification of British Patent No. 570,193.

According to my invention a machine of the type set forth above comprises an intermittently rotated sand container, an intermittently operated shutter controlling the delivery of sand from the container to a blowing chamber, a table for supporting a core-box or mould to be filled, means for moving the table vertically to clamp the core box or mould against the bottom of the blowing chamber, pneumatic means for intensifying the clamping pressure on the core box or mould during filling, and a rotary control for controlling each of the operations or movements and for ensuring automatically that they take place in the correct sequence.

The control may be operated by hand or it may be operated by an electric motor with a push-button switch so that the machine is completely automatic and the operator has simply to place the core-boxes or moulds on the table and remove them at the appropriate times in the sequences of operations.

One practical form of machine for making foundry cores or moulds in accordance with my invention is illustrated by way of example in the accompanying drawings in which—

Figure 1 is a front elevation of the complete machine.

Figure 2 is a plan.

Figure 3 is a side elevation.

Figure 4 is an elevation on a larger scale and partly in section of the lower end of the machine showing the means for operating the ram and applying pressure to the core-box.

Figure 5 is a sectional elevation of the control mechanism for the machine.

Figure 6 is a horizontal section of the control mechanism.

In the machine illustrated the main part of the supporting frame consists of two rigid vertical columns 10, 11. Mounted on the upper end of the frame at one side is the sand container 12 which is a cylindrical chamber mounted for ro-

2

tation about a vertical axis and divided by radial partitions 13 into, say, six segmental compartments. The container is adapted to be rotated intermittently through a chain 14 and toothed ring 15 by an electric motor 16. The container is open at the bottom but is in contact with a circular plate 17 having an opening 18 leading into the blowing chamber 19. The opening 18 is controlled by an angularly movable shutter 20 operated by a pneumatic cylinder 21.

The blowing chamber is of the known type described in British patent specification No. 570,193 with means for supplying air under pressure to an air belt around the chamber, a wire gauze or like screen on the inner side of the air belt, and a power driven agitator in the chamber. The agitator is driven through V belts 22 by an electric motor 23. Openings are provided in the bottom of the chamber for the discharge of the sand, the position and number of these openings depending on the type of cores or moulds to be made.

The blowing chamber has not been illustrated or described in detail as it is of known type.

The table 24 which supports the core-box or mould to be filled is mounted on the upper end of a ram 25 working in a vertical cylinder 26 which communicates with a pressure chamber 27 through a passage 28 controlled by a spring-loaded valve 29 as shown in Figure 4. This valve is urged towards its seating 30 by a spring 31 bearing against the bottom of the valve head but the valve is normally held open by a spring-loaded plunger 32 which enters the upper end of the chamber 27 and bears on the stem of the valve.

The plunger is guided in an extension 33 of a closure 34 bolted to and closing the upper end of the chamber 27, and a head on the upper end of the plunger carries a cup leather 35 working in an enlarged bore 36 in the closure. The cup leather is held between the head and a disc 37, and springs 38 bearing on the disc normally hold the plunger in its lowermost position in which it holds the valve 29 open. The bore 36 below the cup leather is in communication with the interior of the chamber 27 through one or more passages 39.

The chamber 27 is partially filled with oil and means are provided for admitting air under pressure into the chamber above the surface of the oil.

When the compressed air is admitted oil is forced from the chamber 27 into the ram cylinder 26 by way of the valve 29 and passage 28, and the ram 25 and table 24 are raised to clamp a

core-box or mould which has been placed on the table against the bottom of the blowing chamber 19. When the pressure in the chamber 27 reaches a predetermined value the spring-loaded plunger 32 is forced upwardly against the action of the springs 33 by the pressure acting on the plunger and on the underside of the head. The valve 29 then closes and seals the ram cylinder so that the table is locked in position.

To intensify the upward pressure on the table the upper part 40 of the table is allowed a limited vertical movement relative to the lower part and there is arranged between them a flexible diaphragm 41 of substantially the same area as the table. The periphery of the diaphragm is clamped between the lower part of the table and a clamping ring 42. The relative vertical movement of the upper part 40 of the table is limited by a sleeve 43 which surrounds the table. This sleeve has an engagement with a shoulder on the part 40 and near its lower end the sleeve carries an internal ring 44 between which and the lower part of the table there is a small vertical clearance.

After the valve 29 closes air under pressure is admitted below the diaphragm 41 and owing to the relatively large area of the diaphragm the air applies a very high upward pressure to the table and so to the core-box or mould.

The various operations are controlled by a series of valves and switches which are mounted in vertical alignment in a casing 45 mounted at one side of the machine. Figures 5 and 6 show the arrangement of the control mechanism.

A main supply pipe 46 leads air under pressure from a compressor or other source to a central bore 47 in a hollow pillar 48 having four outlets controlled by valves 49, 50, 51 and 52. A parallel bore 53 in the pillar is also in communication with the valves and has connected to it an exhaust pipe 54 leading to atmosphere. One valve controls the supply of air to the blowing chamber 19 through a pipe 55, another controls the supply of air through a pipe 56 to the air cylinder 21 for the shutter 20, a third valve controls the supply of air through a pipe 57 to the space below the diaphragm 41, and the fourth valve controls the supply of air through a pipe 58 to the pressure chamber 27.

Below the valves are two electric switches 59 and 60 controlling respectively the energising of the motor 16 for driving the sand container and the motor 23 for driving the agitator in the blowing chamber.

The valves and switches are selectively actuated in the required order by cams 61 on a rotatable vertical spindle 62 provided at its upper end with a handle 63. The cams actuate the valves and switches through pivoted rockers 64 carrying rollers for engagement with the cams and the valves and switches to reduce friction.

The sequence of operations when the handle 63 is rotated step by step in one direction is as follows:

The motor 16 is switched on to rotate the sand container 12, and air is admitted to the cylinder 21 which opens the shutter 20 and allows sand to pass into the blowing chamber. The container is then stopped and the shutter is closed.

Air is admitted into the pressure chamber 27 to force oil out of that chamber into the ram cylinder and raise the table 24 to clamp the core-box or mould against the bottom of the blowing chamber 19. When a predetermined pressure has been reached the plunger 32 is raised and

the valve 29 closes, and air is then admitted under the diaphragm 41 to intensify the upward pressure on the core-box or mould.

Next air under pressure is admitted to the blowing chamber and the agitator in the chamber is driven. After a predetermined time interval sufficient to allow the core-box or mould to be filled, the air is cut off from the blowing chamber and the agitator is stopped and the chamber is connected to exhaust to release the pressure.

The air feed to the space under the diaphragm 41 is then cut off and this space is connected to exhaust and the air supply to the pressure chamber 27 is cut off and that chamber is connected to exhaust. The pressure on the spring-loaded plunger 32 is thus relieved and the plunger opens the valve 29 between the ram cylinder and the pressure chamber so that oil can return from the ram cylinder to the pressure chamber and the ram and table can descend under gravity to allow the filled core-box or mould to be removed.

Preferably at the same time as the pressure in the pressure chamber 27 is relieved the sand container is set in motion again and the shutter is opened to refill the blowing chamber, and the cycle of operations starts again.

To speed up production sliding carriages 65, 66 may be arranged on opposite sides of the table of the machine and at the same level as the table in its lowered position, each carriage having wheels running on rails spaced apart at a distance greater than the width of the table. A core-box or mould is prepared on one carriage and the carriage with the core-box or mould on it is slid over the table which lifts the carriage off into rails and takes it up with the core-box or mould. Meanwhile another core-box or mould is being prepared on the other carriage, and after the first core-box or mould has been filled and the table has returned to its lowered position the first carriage is slid off to one side of the table and the second is slid on from the other side.

I claim:

1. A machine of the type set forth for making foundry cores and moulds comprising a sand container, a blowing chamber below said container, means for feeding sand intermittently from said container into said chamber, a table below said chamber for supporting a mould to be filled, an hydraulic ram on which said table is mounted and which is adapted to raise the table vertically to clamp the mould against the bottom of the blowing chamber, a passage connecting the lower end of the ram cylinder and a pressure chamber containing oil, means for admitting air under pressure to said chamber above the oil to force the oil into the ram cylinder, a spring-loaded valve in said passage, a pressure-responsive device within the chamber operatively connected with said valve, spring means acting on said device to normally move the latter to a position to open said valve, said device being subjected to the pressure within the chamber and movable when a predetermined pressure is reached therein to allow said valve to close, and pneumatic means associated with said table for intensifying the clamping pressure on the mould when the valve is closed.

2. A machine of the type set forth for making foundry cores and moulds comprising a sand container, a blowing chamber below said container, means for feeding sand intermittently from said container into said chamber, means

for feeding air under pressure into said chamber, a table below said chamber for supporting a mould to be filled, said table having a relatively movable upper part to receive the mould, a flexible diaphragm substantially co-extensive with the table between the table and the said relatively movable mould-receiving part, an hydraulic ram carrying said table and working in a vertical ram cylinder, a pressure chamber containing oil adjacent to the ram cylinder, a passage connecting the bottom of the ram cylinder and the pressure chamber, a spring-loaded valve in said passage, means for admitting air under pressure to said pressure chamber to force oil from the chamber through said passage into the ram cylinder to raise the ram and clamp the mould against the bottom of the blowing chamber, a pressure-responsive device within the pressure chamber operatively connected with said valve, spring means acting on said device to move the latter to a position to maintain said valve normally open, said device being subjected to the pressure within the pressure chamber and movable when a predetermined pressure is reached therein to allow said valve to close, and means for subsequently admitting air under the diaphragm to intensify the clamping pressure on the mould.

3. A machine of the type set forth for making foundry cores and moulds comprising a sand container rotatable about a vertical axis, electrical means for driving said container intermittently, a blowing chamber arranged below said container, pneumatically operated means for feeding sand intermittently from said container into said blowing chamber, a mould-supporting table below said blowing chamber, an hydraulic ram on which said table is mounted for moving said table vertically to clamp a mould against the bottom of the blowing chamber, pneumatic means for forcing oil from a pressure chamber into the ram cylinder, means including a device within the pressure chamber and subjected at all times to the pressure therein for closing the communication between the pressure chamber and the ram cylinder when a predetermined pressure is reached, pneumatic means associated with said table for intensifying the clamping pressure on the mould, grouped valves and switches for controlling the supply of compressed air and current to initiate the various operations of the machine, and a rotatable spindle carrying cams

for actuating said valves and switches automatically in the correct sequence.

4. A machine of the type set forth for making foundry cores and moulds comprising a cylindrical sand container rotatable about a vertical axis, means for rotating said container intermittently, a fixed plate over which said container works, a blowing chamber arranged below said plate, an opening in said plate leading into said blowing chamber, a pivoted shutter for covering and uncovering said opening to control the delivery of sand from said container into said blowing chamber, pneumatic means for operating said shutter, a mould-supporting table below said blowing chamber, an hydraulic ram on which said table is mounted for moving said table vertically to clamp a mould against the bottom of the blowing chamber, pneumatic means for forcing oil from a pressure chamber into the ram cylinder, means including a device within the pressure chamber and subjected at all times to the pressure therein for closing the communication between the pressure chamber and the ram cylinder when a predetermined pressure is reached, pneumatic means associated with said table and moving a part of said table relative to another part to intensify the clamping pressure on the mould during filling, and a rotary control for controlling each of the operations of the machine and for ensuring automatically that these operations take place in the correct sequence.
